(57) **CLAIM**

We claim the ornamental design for a coded information reader, as shown and described.

DESCRIPTION

FIG. 1 is a front perspective view of a coded information reader according to a second embodiment of the present invention.

FIG. 2 is a front view thereof;

FIG. 3 is a rear view thereof;

FIG. 4 is a perspective left view thereof;

FIG. 5 is a right side view thereof;

FIG. 6 is a top view thereof; and,

FIG. 7 is a bottom view thereof.

The portions shown in broken line are not claimed.
